UNITED STATES PATENT OFFICE.

THOMAS J. RICHARDS, OF PHILADELPHIA, PENNSYLVANIA.

IMPROVEMENT IN SHIRT-BOSOM PROTECTORS.

Specification forming part of Letters Patent No. 147,573, dated February 17, 1874; application filed January 28, 1874.

To all whom it may concern:

Be it known that I, THOMAS J. RICHARDS, of the city of Philadelphia, State of Pennsylvania, have invented certain new and useful Improvements in Shirt-Bosom Stretchers and Protectors; and I do hereby declare the following to be a full, clear, and exact description of the same, reference being had to the accompanying drawings making a part of this specification, in which—

Figure 1 represents a front view of the stretcher and protector, and Fig. 2 represents a vertical section through the same.

My invention relates to a shirt-bosom stretcher and protector as a new article of manufacture, it being composed of paper-board and fastened to the shirt at the top and bottom to keep it in proper position.

To enable others to make and use my invention, I will proceed to describe the same with reference to the drawings.

The stretcher and protector A is made of paper or pasteboard, of sufficient thickness or strength to maintain its flat or uncreased condition, and should conform to the shape and form of a shirt-bosom. For summer use I prefer to make the stretcher of perforated paper-board, as being cooler. For winter use it may be of plain board imperforate. The top of the stretcher is fastened to the collar or neck band of the shirt by a stud or button, a, and the lower end of it is similarly fastened, as at b, to the lower part of the shirt-bosom. For the

lower fastening, an eyelet-hole may be worked in the lower part of the shirt-bosom, through which the shank of a screw-stud is passed, and a slot, c, is formed in the stretcher so as to adapt it to the position of the eyelet and screw-stud. The shank of the screw-stud after passing through the eyelet in the shirt-bosom, then passes through said slot, and the nut-head of the screw-stud is screwed onto the shank. To give greater strength to the paper-board where the head of the screw-stud rests, a washer, e, of paper-board or other substance may be placed.

Common buttons, as fastenings for the stretcher, would not answer so well as the screw-studs, as the paper-board is too rigid to receive the common button.

This stretcher is quite cheap, so much so that when soiled or creased it may be thrown away and a fresh one applied.

What I claim as a new article of manufacture is—

A shirt-bosom stretcher and protector made solely of paper-board and united to the neck-band by a stud, as at a, and fastened at the lower portion of the shirt-bosom by the screw-stud b adjustable in the slot c, as and for the purpose described and set forth.

THOS. J. RICHARDS.
